UNITED STATES PATENT OFFICE.

CHARLES H. CURRAN AND ENOCH WHALLEY, OF HOLYOKE, MASSACHUSETTS.

SAFETY-PIN.

SPECIFICATION forming part of Letters Patent No. 555,723, dated March 3, 1896.

Application filed December 23, 1895. Serial No. 572,968. (No model.)

To all whom it may concern:

Be it known that we, CHARLES H. CURRAN and ENOCH WHALLEY, citizens of the United States of America, residing at Holyoke, in the 5 county of Hampden and State of Massachusetts, have invented new and useful Improvements in Safety-Pins, of which the following is a specification.

This invention relates to safety-pins, and 10 has for its object such arrangement and construction of the guard or shield for the point of said pin as will permit the latter to be disengaged from said point-shield by pressing together the two sides thereof; and the invention 15 consists in the peculiar construction of said shield from a metal blank and its adaptation to the point of the pin.

In the drawings forming part of this specification, Figure 1 is a side elevation, and Fig. 20 2 is a plan view of the same. Fig. 3 is a sectional view taken on line $x-x$, Fig. 2, looking toward the point of the pin. Fig. 4 is a plan view of the metal blank from which the point-shield is made.

25 In the drawings, A is a safety-pin of the usual construction, a spring-loop being formed in the length of wire constituting the back and the point end in the usual manner and having attached to the lower of said two wires 30 the point-shield B.

The point-shield B is made of any suitable spring metal, the configuration of the blank from which it is bent up being shown in Fig. 4. Said blank is constituted principally of 35 the two side portions D D, having attached thereto the two arms D' D' and integral therewith. The lines on which said blank is bent to form the point-shield are shown dotted on Fig. 4. In forming said point-guard the blank 40 is first bent on the line E, which brings the two sides D D and the two arms D' D' opposite each other; but, as will be seen by the position of the arms D' in the blank relative to the dotted line E, the arm on the right-hand side of the blank, as shown in the drawings, will be in a position above the arm D' on the left-hand side of the blank shown in Fig. 4. After said blank has been folded on the line E, as above described, the said 45 arms D' D' are bent respectively to the right and to the left on the lines E' and around the

edge of the upturned side D on the side opposite to said arm D'. When said arms have been so bent, the positions thereof relative to each other are shown in Fig. 3, wherein it 55 will be observed that in bending the blank on the line E it is bent on such circle as to fit the end of the wire to which it is to be attached by soldering, leaving a space between the two sides D about equal to the diameter 60 of the wire, and it will be observed that the arms D', bent on the lines E' to the right and to the left respectively, are so bent as to leave a space F between the inner face of the arm D' and the outer face D of said point-shield. 65 The circular ends of the blank are bent inwardly toward each other and outwardly again, whereby two inwardly-projecting ribs G are formed lying substantially parallel with the wire forming the pin and so maintained 70 by the spring action of the metal blank bent upon itself on the line E. The said ribs or projections so held in contact with each other inclose the point of the pin, the spring action of the metal blank being sufficient to hold it 75 securely therein against the spring action of the loop in the wire.

By referring to Figs. 2 and 3 it will be seen that the part D' of each side of the blank is connected to the part D of the opposite side 80 of said blank. Hence pressure being applied to the parts D' in the direction indicated by the arrows tends to separate the parts D of the point-shield, as indicated by the arrows on the upper part G of said Fig. 3, said action 85 being also indicated by the oppositely-pointed arrows on Fig. 2, thereby releasing the pin-point, and upon pressure against the parts D' being relaxed the spring action of the sides of the blank resulting from the bend therein 90 on the line E immediately moves the said parts D toward each other until the projections or ribs G come again in contact. The outward bend of the circular edges of the sides D above the rib G forms an easy entrance 95 for the pin-point past the ribs G and into the space between the opposite sides D.

By the construction herein described it will be seen that the point of the pin can be released by a simple pressure on the two parts 100 D' on each side of the point-shield regardless of the thickness of the material inclosed be-

tween the two wires of the pin, which is a material advantage over the construction of pins whose points are engaged under a downwardly-projecting lip, from which it is frequently difficult to disengage said point when the pin has been passed through a considerable thickness of material.

Having thus described our invention, what we claim, and desire to secure by Letters Patent, is—

In a safety-pin, the point-shield thereon consisting of two parallel sides inclosing the point of said pin, each of said sides having

an inwardly-projecting rib thereon, near its upper edge, and each having an arm integral therewith which is bent around the end of the opposite side to a position substantially parallel with said side, whereby the movement of the said arms toward each other causes a movement of the point-inclosing sides in an opposite direction, substantially as described.

CHARLES H. CURRAN.
ENOCH WHALLEY.
